UNITED STATES PATENT OFFICE

ARTHUR A. ARNOLD, OF HAMDEN, CONNECTICUT, ASSIGNOR TO THE A. C. GILBERT COMPANY, OF NEW HAVEN, CONNECTICUT, A CORPORATION OF MARYLAND

DESIGN FOR A COMBINED GUARD, SUPPORT, AND DRIVING MEANS FOR A FAN

Application filed January 27, 1933. Serial No. 47,020. Term of patent 14 years.

To all whom it may concern:

Be it known that I, ARTHUR A. ARNOLD, a citizen of the United States, residing in Hamden, in the county of New Haven and State of Connecticut, have invented a new, original, and ornamental Design for a Combined Guard, Support and Driving Means for a Fan, of which the following is a specification when taken in connection with the accompanying drawing, in which—

Fig. 1 is a front elevation of a combined guard, support and driving means for a fan showing my new design; and

Fig. 2 is a side elevation thereof.

The ring-like member, the base or support therefor, and the driving means for the fan blades are regarded as important features of the design.

I claim:

The ornamental design for a combined guard, support and driving means for a fan substantially as shown and described.

ARTHUR A. ARNOLD.
